UNITED STATES PATENT OFFICE.

EDISON E. RANDALL, OF KANKAKEE, ILLINOIS, ASSIGNOR TO POPE MACHINE COMPANY, OF CHICAGO, ILLINOIS, A CORPORATION OF ILLINOIS.

HOSIERY DRYING AND FINISHING STRUCTURE.

Application filed March 24, 1924. Serial No. 701,564.

This invention relates to hosiery drying and finishing structures, and it has particular reference to an instrumentality associated with a drying form for engaging and holding on the form a hosiery-article while being dried thereon and which, by reason of its damp condition and its normal tendency to shrink when heat is imparted to its fabric to dry it, would creep up on the form and by reason of such shrinkage be thereby undesirably shortened.

The object, therefore, of the present invention is to provide a hosiery-holding structure adapted to be associated with a hosiery-drying form and to be effective, likewise, to prevent, or at least reduce to a minimum, the upward creeping of a hosiery-article while being dried upon a metallic drying form of the general type, for instance, disclosed in United States Patent No. 1,207,496, to W. D. Butz.

It is within the contemplation of my inventive-concept to provide a hosiery-hollow structure comprising, in general, an expansible member or element suitably maintained in relation to the drying surfaces of the form and displaceable in respect to those surfaces during the operation of "boarding" the hosiery-article on the form and which element is readily restored to normal, active position without much if any effort on the part of the operator.

In the drying and finishing of hosiery, under present-day practice and wherein heated metal forms are very generally employed, it has been found that when a wet or damp piece of hosiery is placed upon the form the heat thereof develops a normal tendency in the hosiery to shrink very rapidly and thus to creep on the form and its length be thereby materially changed. Various means and devices have been proposed to hold the hosiery during the boarding operation and to prevent such shrinkage; but in most of these instances the means and devices have been more or less unsatisfactory because they either fail to function efficiently or else are unsatisfactory because if they engage the fabric of the hosiery firmly enough, they mark or deface the same and render it unmarketable. As the result of long-continued experiments and tests, I have developed the subject-matter of the present case; and in this connection I may state that my inventive-concept is predicated

upon the discovery that if an expansible element is utilized for engaging the hosiery and holding it against the surfaces of the form, the results are eminently satisfactory while, at the same time, the operation of the device is a most automatic and requires little or no actuation by the operator, usually called a "boarder."

With the foregoing and other objects in view, my invention resides in the structures hereinafter described and illustrated in the accompanying drawings; though in this connection I wish it to be understood that the particular embodiments herein revealed are merely illustrative, that the invention is susceptible of other embodiments, and that the several embodiments are susceptible of a wide range of modification and variation without departing from the salient features and underlying principles of the invention.

In the accompanying drawings:

Figure 1 is a view in front elevation of a hosiery-drying form equipped with one type of hosiery-holder structure constructed in accordance with my invention;

Fig. 2 is a view in horizontal section, on the line 2-2, Fig. 1;

Fig. 3 is a similar view on line 3-3, Fig. 1;

Fig. 4 is a fragmentary view showing the expansible member in its normal hosiery-engaging position;

Fig. 5 is a similar view showing the expansible member displaced from normal position and out of engagement with an article of hosiery;

Fig. 6 is a fragmentary view of a modification thereof, and involving the utilization of a plurality of expansible members;

Fig. 7 is a similar view, also of a modification, showing the expansible member provided with means for restricting its expansibility;

Fig. 8 is a view similar to Fig. 1 of a somewhat different embodiment of the invention, involving the provision of a pivoted member on which the expansible member has a rolling movement and by which its normal and abnormal positions may automatically be effected;

Fig. 8^a is a fragmentary view in edge elevation of a somewhat modified type of structure;

Fig. 9 is a view in horizontal section on the line 9-9, Fig. 8;

Fig. 10 is a fragmentary view, showing the parts in the position which they assume when the expansible member is out of its normal hosiery-engaging position;

5 Fig. 11 is a fragmentary view of a modification of the type of structure shown in Figs. 1 to 7 but embodying a feature which characterizes the embodiment of Fig. 8;

10 Fig. 12 is a fragmentary view, in detail, of certain of the parts shown in these structures;

15 Fig. 13 is a view, in front elevation, of apparatus which includes a series of forms—each having associated therewith the type of expansible member and the controlling device therefor shown in Figs. 8 to 10, together with mechanism for simultaneously actuating a plurality of the controlling devices;

20 Fig. 14 is a fragmentary view, in section elevation thereof; and

Fig. 15 is a view in horizontal section, on the line 15—15, Fig. 13.

25 In these drawings, the reference-character 1 designates a hosiery-drying form, of the general type disclosed in the aforementioned Patent No. 1,207,496, and which includes a base-portion 2 which is adapted to be secured to a pipe (not shown) for supplying a heating-medium to the form, the latter also including a leg-portion and a foot-portion 4 and 5, respectively.

30 Integral with or otherwise attached to the form is a bracket 5^a shown, in this instance, as comprising two members 6 secured at opposite ends by bolts 7. On the bracket is a base-member 8, preferably and as shown of lineal dimensions greater than the widthwise dimensions of the form 1. Upstanding 35 from the base 8 are element-supporting members or posts 9 which are arranged, in this particular instance, adjacent to but spaced from the edges 10 of the form. These upstanding members are, preferably and as shown, inclined to the vertical, and they occupy a position parallel to the edges 10 of the form. The upper extremities of the carrying-elements are out-turned to provide limit-stops 11, or other element-limiting 40 means may be provided.

45 Suspended between the supporting-members 9 and movable thereon is an expansible-element or member 12 which, in this instance, is an elongated, endless, spiral spring, of proper tension and dimensions to perform its required function. The construction and arrangement of this element 12 on its support—as provided by the members 9—are such as to effect a rolling movement of the element as it moves upwardly and downwardly on the form. Moreover, the nature of engagement of the element with the hosiery-article is such that the element may be moved circumferentially of 50 the form when the boarder shifts the article

55 on the form in the operation of lining up the wales of the article with the vertical edges of the form, this insuring a better "finish" to the article. Furthermore, by reason of the open character of the expansible member—due to its spring form and being spirally wound—it presents a limited though effectual contact with the hosiery and, thus, permits the heat of the form to effect its drying function; at the same time permitting the hosiery to ventilate itself, so to speak. The normal position of this expansible-element 12 is adjacent the limit-stops 11 on the supporting-members; and, then, the greater portion of it is in engagement 60 with the two sides 13 of the form, its resilient character permitting it to assume an arcuate contour to conform to the curved sides of the drying-form. Thus, the hosiery-article 14 on the form will be engaged 65 by the expansible-element practically throughout its widthwise area between its edges as defined by the edges 10 of the form.

70 In operation, the boarder (in placing the hosiery-article on the form) will stretch the same downwardly and in the direction of the base of the form and, as her hands in thus placing the hosiery-article on the form, come into contact with the expansible-member 12, she will displace the same from the 75 aforementioned normal position and, if necessary, to a position below the extreme lower edge of the hosiery-article. As soon as the boarder removes her hand from the form and, thus, out of contact with the hosiery-article, the expansible-member 12 will quickly return—by a rolling action—to its 80 upper normal position and engage the fabric of the hosiery and thereby effect an action thereof such that creeping of the hosiery is prevented or at least reduced to a minimum. It will be understood that the 85 inclined arrangement of the supports 9 contributes to the automatic return of the expansible-member to its aforementioned normal position. The character of the expansible-member is such as to produce a uniformly firm holding action and, at the same time, produce no marking or defacing of the fabric, or contribute at all to the wrinkling of 90 the fabric as it tends to creep during the 95 drying-operation. Besides, the extended contacting surface of the expansible-member with the fabric effectually holds it almost entirely throughout its widthwise dimension and this is desirable toward effecting the best results.

100 From this description, it will be evident that I have provided a type of hosiery-holder which engages the hosiery-article practically throughout its width and effectually holds it against creeping and, thus, from shrinkage or wrinkling. At the same time, the action of the expansible-member is automatic, both for its displacement and for 105

its restoration to normal position, so that the operator is in no way called upon to manipulate the holder nor is her manipulation of the hosiery, in straightening the same on the form, at all interfered with by the presence of the holder.

If it is found that one expandable-member is insufficient to hold the hosiery on the form in any particular instance or by reason of the character of the fabric in the hosiery, an additional expandable-member 15 may be provided, as shown in Fig. 6, and which may be mounted on the supporting-members, and its movement thereon and action in connection with the fabric will be the same as already explained in reference to the other expandable-element 12.

If it be desired to restrict the expandability of either or both of the expandable-elements 12 and 15 (according to which type is used), means may be associated therewith for that purpose, and in this instance I have shown annular members, in the form of rings 16, encompassing the portions of the expandable-members between the supporting-members 9 and the edges 10 of the form. These rings, when not in use, may be moved onto the supporting-members and rest at their bases, all as shown in Fig. 7.

In Fig. 8, I have disclosed a somewhat different type of structure, but one clearly within the principles of my invention. In this instance, there extends upwardly from the base 8 a pair of posts or supporting-members 17 and 18, both of which have outwarded extremities 19. The supporting-member or post 17 is stationary on the base 8, whereas the other member 18 is pivoted to a fulcrum-piece 20 upstanding from the base 8 to permit the member 18 to be swung away from the edge of the form. This member 18 is provided with an extension 21 to which is secured an expandable spring 22 having a normal tendency to swing the member on its fulcrum and thereby move its upper end outwardly and away from the form. At opposite sides of the supporting-members or posts 17 and 18 are two "edge-pieces" 28 which diverge downwardly. The edge-pieces on the stationary members 17 are bent inwardly and are attached to the member itself. Outstanding from this member, and in approximate alinement with the edge 10 of the form, is a limit-stop 23. The edge-pieces on the supporting-member or post 18 terminate in T-pieces 24, the inner extremities of which are attached to the post, while the outstanding sections constitute limit-stops.

Suspended between and slidable on the supporting-members or posts 17 and 18 is an expandable-member 25 corresponding to the expandable or spring member 12 in the first-described embodiment. In this instance, however, the downward displacing of the

element 25 toward the base 8 as effected by the operator when pulling the stocking down on the form to stretch it thereon causes this element to engage the edge-pieces and be expanded laterally so as to displace its engaging portions away from the form. This displacing movement of the expandable-member will, when it engages the T-stops on the supporting-posts 18, enable the spring 22 to function and rock this member on its fulcrum and cause it to be held in such position. On the upper extremity of the member 18 is a handle 26 which permits the operator to move the member 18 inwardly toward the form, and to a slightly overthrown position—indicated by dotted lines in Fig. 8—there being sufficient clearance between the upper end 20^a of the fulcrum-piece 20 and the top of the slot 21^a in the pivot-portion of the element 21 to permit such overthrow of the member 18 and against the reactive influence of the spring 22 which, then, has a normal tendency to swing the member back in the opposite direction and, thus, against the slight pull of the expandable member which, while the member is in its overthrown position, will slide upwardly on the members 17 and 18 and, thus, automatically be caused to resume its upper, normal position and in engagement with the stops 19. It is to be understood that the tension of the expandable member is not such as to interfere with the action of the spring 22 actuating the member 18, as just explained. Moreover, this member is manually moved toward normal position to permit the expandable member to slide up on it in the manner set forth.

From the foregoing description of this second embodiment, it will be understood that when the operator pulls the stocking down toward her and manipulates the top toward the base of the form, she, by reason of the engagement of her hands with the expandable-member 25, moves the same downwardly and against the limit-stops on the posts, and by this action positions the expandable-element to permit the spring 22 to rock the supporting-member 18 on its fulcrum and into the position shown in Fig. 10. At the same time, the element 25 will be expanded transversely by the edge-pieces 28 so that it will be entirely disengaged from the form. Then, when the operator manually actuates the member 18 to move it back toward the edge of the form and somewhat beyond normal position and, thus, at an angle to the plane of the opposite member 17, as already described, the expandable-member 25 will slide upwardly on both members 17 and 18 and resume its normal position and engage the hosiery and hold it until displaced therefrom by the operator.

In Fig. 8^a, I have shown the type of structure of the embodiment of Figs. 1 to 7 as

provided with element-spreaders 27 similar to those on the supporting-posts 17 and 18 of the embodiment of Fig. 8, these contributing to support the expansible-element 12 and thereby disengage it from contact with the form.

In Figs. 13 to 15, I have illustrated a somewhat different embodiment of the invention, this involving primarily the provision of mechanism in association with a series of the forms whereby a plurality of the member-controlling devices—of the general type in this instance shown in Figs. 8 to 10—may be simultaneously actuated. This mechanism includes a rod-guiding element 29 on the base-portion of each form 1. This element is provided with a recess 30 in which an actuating bar 31 is slidably supported. The bar is elongated and of a length to correspond to the pair of forms mounted on the table T. It will be understood that when the lever 33 is actuated—toward the right, as viewed in Fig. 13—each angle piece 32 will engage the adjacent extension 21 of the member 18 and actuate this member on its fulcrum, on the fulcrum piece 20, and into the tilted position shown in Fig. 10, for instance. While the member 18 is thus moving into its tilted position, the spring 22 effects a pull on the extension 21 to facilitate movement of the member; and while this is occurring, each expansible member 25 is at first expanded to the extent that the member is tilted, whereupon it slides down on the members 17 and 18 to a position corresponding to that shown in Fig. 10. It then is still in a stretched condition so that, when the member 18 is manually moved toward the form and to a position slightly angular to the vertical, the expansible member will slide up on the members 17 and 18 into a position, corresponding to that shown in Fig. 8. Means are thus provided for actuating—through the lever 33—a plurality of the member-controlling devices 18, so that the several expansible members 25 may be simultaneously rocked on their fulcras and to a position corresponding to that shown in Fig. 10. When the operator shall have placed hosiery on the several forms 1, he can manually restore each member 18 to its normal vertical position and thereby effect a re-positioning of the flexible member 25 to produce an engagement between it and the hosiery.

What I claim is:

1. A hosiery-holder structure including upstanding spaced posts, an annular hosiery-engaging element extending between the posts and circumferentially expansible thereon, and a hosiery drying and shaping member upstanding between the posts and encompassed by said element to counteract the tendency of a hosiery-article to slip thereon.

2. A hosiery-holder structure including a stationary base, a pair of oppositely-disposed supporting-members upstanding therefrom and independent of each other, an annular, expansible element movably sustained by and stretched between the members so that the portions therebetween have a normal tendency to assume a parallel form-engagement relation, and a hosiery drying instrumentality projecting through and engaged by the element.

3. A hosiery-holder structure including a hosiery finishing instrumentality, a stationary base associated therewith, an annular circumferentially-expansible element operatively associated with the base and instrumentality, and a plurality of supporting-members upstanding from the base and spaced from the instrumentality and projecting through the element and spaced apart on the base to effect a stretching of the element and a consequent normal tendency of portions thereof to assume a substantially parallel relation to each other.

4. A hosiery-holder structure including a supporting-device comprising a bracket and sustaining-members upstanding therefrom, in combination with an expansible element stretched between the members and movable thereon, and a form projecting through the element and engageable thereby.

5. A hosiery-holder structure including a supporting-device comprising a bracket and sustaining-members upstanding therefrom, in combination with an expansible element stretched between the members and bodily rollable thereon, and a form projecting through the element and engageable thereby.

6. A hosiery-holder structure including a supporting-device comprising a bracket and supporting-members upstanding therefrom, and an expansible hosiery-engaging element suspended between the members and rollable thereon in relation to the bracket.

7. A hosiery-holder structure including a supporting-device comprising a base and element-supporting members upstanding therefrom and having out-turned upper extremities, and a hosiery-engaging element suspended between and rollable on the members and engageable with the out-turned ends.

8. A hosiery-holder structure including a supporting-device comprising a base and element-supporting members upstanding therefrom, a hosiery-engaging element suspended on the members and bodily rollable thereon to any of a plurality of positions in relation to the base, the members carrying means for limiting the rolling movement of the element, and a hosiery-drying form associated with and projecting through the element and engageable by it at any of a plurality of points thereon.

9. A hosiery-holder structure including a

supporting-device comprising a bracket and supporting-members upstanding therefrom and inclining toward each other, a hosiery-engaging element suspended between the members and bodily rollable thereon to any of a plurality of positions in relation to the bracket, and a hosiery finishing device upstanding between but independent of the supporting members and engageable by the element when in one position on the supporting members, said element being separable from the device when in a different position.

10. A hosiery-holder structure including a supporting-device comprising a base and element-supporting members upstanding therefrom, and a hosiery-engaging element suspended on the members and rollable thereon in relation to the base, the members carrying 20 means for limiting the rolling movement of the element and inclining from the vertical to effect expansion of the element as the same rolls thereon.

11. A hosiery-holder structure including a supporting device comprising a form-attaching bracket, a base carried by the bracket, and element-supporting members upstanding from the base and inclining toward each other, and a hosiery-engaging element rollable on the members and expandable while 30 rolling on the members.

12. A hosiery-holder structure including a supporting device comprising a form-attaching bracket, a base carried by the bracket, and element-supporting members upstanding from the base and inclining toward each other, and a hosiery-engaging element rollable on the members and expandable while 40 rolling on the members, said members carrying means for restricting movement of the expandable element.

13. A hosiery-holder structure including a plurality of upstanding supporting-members, an expandable element suspended between the members, and means associated with the expandable-element for restricting its expansibility.

14. A hosiery-holder structure including a supporting-device comprising a bracket and 50 supporting-members upstanding therefrom, an expandable hosiery-engaging element suspended between the members and rollable thereon in relation to the bracket, and a ring encompassing the expandable-element.

55. 15. A hosiery-drying structure including a drying form, a bracket thereon having a base, element-supporting members upstanding therefrom and in angular arrangement with respect to the form, and an element 60 movable and circumferentially expandable on the members and engageable with surfaces of the form.

16. A hosiery-holder structure for drying forms including a base, element-supporting structures upstanding therefrom,

one at least of the members being pivoted on the base, means associated with the pivoted member having a normal tendency to actuate it in relation to its companion member, and an expansible-element movable on the members and operating during such movement to operate the pivoted member.

17. A hosiery-holder structure for drying forms including a base, element-supporting structures upstanding therefrom, one at least of the members being pivoted on the base, means associated with the pivoted member having a normal tendency to actuate it in relation to its companion member, an expansible-element movable on the members and operating during such movement to operate the pivoted member, and means carried by the pivoted member for restoring it to normal position and thereby cause the expansible-element automatically to be restored to normal position.

18. A hosiery-holder structure for drying forms including a base, element-supporting members upstanding therefrom and one at least of the members being pivoted on the base and carrying an extension, a spring attached to the extension and base and operating to actuate the pivoted member, and an expansible hosiery-engaging element rollable on the members.

19. A hosiery-holder structure for drying forms including a base, element-supporting members upstanding therefrom and one at least of the members being pivoted on the base and carrying an extension, a spring attached to the extension and base and operating to actuate the pivoted member, an expansible hosiery-engaging element rollable on the members, and means associated with the members for effecting expansion of the element during such rolling movement.

20. A hosiery-drying structure including a drying form in combination with a bracket thereon, a base associated with the bracket, element-supporting members upstanding from the base and one at least of which is fulcrumed thereon for movement away from the form, means active on this member influencing its movement in relation to the form, an expansible-element rollable on the members and engageable with the form, and means on the members for effecting its expansion and separation from the form.

21. A hosiery-holder structure including a plurality of upstanding supporting-members, and an expandable element movably suspended between the members and flexible to permit its bodily movement on the supporting-members, whereby lining-up of the wales of an engaged hosiery-article may be effected.

22. A hosiery-holder structure including a plurality of upstanding supporting-members

bers, and an expansible element movably suspended between the members, said element being spirally wound and, thus, being of open character, whereby steam and the like from an engaged hosiery-article may penetrate the element.

23. A hosiery-drying structure including a drying form in combination with a bracket thereon, a base associated with the bracket, element-supporting members upstanding from the base and one at least of which is fulcrumed thereon for movement away from the form, means active on this member for actuating it toward the form, an expansible-element rollable on the members and engageable with the form and operating during its rolling movement to actuate the movable member away from the form and spirally wound to present hosiery-engaging instrumentalities of open character, and means on the members for effecting its expansion and separation from the form.

24. A hosiery drying and shaping structure including a support, a series of drying forms on the support and each provided with a base, a bar-guiding element on each

base, a bar slidably mounted in the several guiding members and common to each of the series of forms, a plurality of angle pieces on the bar one adjacent each form of the series, a pivoted hand-lever connected to the bar whereby a plurality of the pivoted members may be simultaneously actuated in relation to the several forms, and means associated with each pivoted member for influencing its action.

25. Hosiery drying and shaping apparatus including a support, a plurality of forms on the support and arranged in series, element-supporting members associated with each form and one of which members is pivoted, means associated with the pivoted member and operating to influence its movement in relation to its companion member, an element movable and circumferentially expansible on the members, a member-actuating element common to the several pivoted members and engageable therewith to actuate them, and a hand-lever for operating the member-actuating element.

In testimony whereof I affix my signature.

EDISON E. RANDALL.
